Primary Examiner — Elizabeth Albert*Assistant Examiner* — Kelley Donnelly*(74) Attorney, Agent, or Firm* — Richard L. Miller(57) **CLAIM**

The ornamental design for a traveler's tote, as shown and described.

DESCRIPTION

FIG. 1 is a left front top perspective view of a traveler's tote showing my new design.

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof; and,

FIG. 8 is a cross section view taken on line 8-8 in FIG. 1.

It is to be understood that any portion of any figure shown in broken lines are for environmental purposes only and form no part of the claimed design; and

The broken away portion of the design embraced by a bracket indicates that no particular length is claimed.
